UNITED STATES PATENT OFFICE

FELIX A. LACKS, OF PELHAM MANOR, NEW YORK

DESIGN FOR A LADY'S WOVEN HAT

Application filed January 10, 1931. Serial No. 38,263. Term of patent 7 years.

To all whom it may concern:

Be it known that I, FELIX A. LACKS, a citizen of the United States, residing in Pelham Manor, in the county of Westchester, State of New York, have invented a new and original Design for Lady's Woven Hat, of which the following is a specification, reference being had to the accompanying drawing, forming a part thereof, in which:

The figure is a perspective view of a hat showing my new design.

I claim:

The ornamental design for a lady's woven hat, as shown.

FELIX A. LACKS.
